STABILIZER WITH CONDENSER
MODULATOR

Louis L. Weisglass, New York, N. Y., assignor to
Picker X-Ray Corporation Waite Manufacturing Division, Inc., Cleveland, Ohio, a corporation of Ohio

Application July 3, 1947, Serial No. 758,877

7 Claims. (Cl. 250—97)

1

This invention relates to X-ray systems and more particularly to improved means for maintaining the discharge current flowing through the tube substantially constant by the use of a condenser in the stabilizer circuit.

The use of a variable resistance in the central grounded circuit of the high tension transformer of an X-ray tube system for the purpose of stabilizing the discharge current flowing through the tube is disclosed in my United States patent, No. 2,319,378, granted May 18, 1943. In this patented system as long as the current wave shape is maintained there is always a fixed relationship between its average and peak value. If changes in the shape of the current wave occur, this relationship between average and peak values of the current is greatly disturbed. Many factors in the X-ray system tend to change the shape of the current wave. The error thus introduced may theoretically amount to several hundred percent.

The present invention relates to the use of a condenser in the central grounded circuit of the high potential transformer feeding an X-ray tube, for the purpose of stabilizing the discharge current flowing through the tube regardless of the wave shape which the current may take. The condenser is an accumulator for quantities of electricity which integrates the current flow during each half cycle so that the peak voltage reached by the condenser represents an integration of the current flowing through the time period of the half cycle. This condenser peak voltage is proportional to the average value of the feeding current regardless of the shape of the current wave.

An object of the present invention is to provide an X-ray system wherein the milliamperage flowing through the X-ray tube is maintained substantially constant, regardless of changes in the current wave shape as it appears in the central grounded circuit of the high tension transformer.

Another object of the present invention is the provision of an X-ray system wherein any tendency for the discharge current to vary, automatically causes a variation in the filament heating current, thereby maintaining the milliamperage of the discharge current substantially constant, regardless of changes in the wave shape of the current flowing through the tube.

Another object of the present invention is the provision of an X-ray system wherein current flow charging a condenser in the excitation circuit automatically varies the current flow through the plate circuit of an amplifier tube, which in turn renders an auxiliary circuit operative to

2

cause a variation in the filament heating current inversely to the variation in the discharge current, thereby maintaining the latter substantially constant.

5 Another object of the present invention is to provide a bias on an amplifier tube control grid in a circuit controlling the filament heating means mentioned above, together with a control circuit subject to the discharge current through the X-ray tube which, when applied to said control grid, will vary its bias, if necessary, to hold said discharge current at a desired value.

Still another object of the present invention comprises the circuits defined in the preceding 15 paragraph wherein said control circuit is pre-charged to provide substantially the normal expected bias on said control grid together with means for removing said normal bias from said control grid and applying said control circuit thereto coincident with the energization of the X-ray tube, so that any slight variation from the desired value of the discharge current may be immediately corrected.

20 A further object of the present invention is the provision of means for selecting the milliamperages desired for an X-ray tube exposure which at the same time will select a suitable control condenser for connection in the central grounded circuit of the high tension transformer and if necessary a suitable variable compensating voltage in the control circuit mentioned in the preceding paragraph which governs the bias on the control grid of the amplifier tube. Thus, automatically all of the factors are selected which are 25 necessary for maintaining the desired discharge current through the tube at the moment the tube is energized.

30 Other objects and advantages of the present invention will be apparent to those skilled in the art and the essential features thereof will be set forth in the appended claims.

35 In the drawings, the sole figure is a diagrammatic illustration of a stabilizer system utilizing my invention.

40 In the drawing I have illustrated an X-ray tube 19 having an anode 11 and a cathode or filament 12 which are energized through lines 13 and 14 through a bridge rectifier 15 which in turn is supplied with current from a high potential transformer 16. The transformer has a primary 16a and a secondary 16b which has a central grounded circuit in which there is provided a milliammeter 17 and one or more control condensers 18a, 18b and 18c, as will presently appear. Preferably, a contactor switch 19 for ini-

tiating an X-ray exposure is in series with the transformer primary 16a. This contactor switch is controlled by relay 20 which is energized from the source L3, L4 when the exposure button 21 is depressed. A relay 22 is provided in parallel with the relay 20 for a purpose which will later appear. When the X-ray tube is energized current flow appears in the central grounded circuit containing the condenser 18a. It is a purpose of the present invention to utilize the peak voltage of this control condenser to stabilize the current flowing through the X-ray tube.

The alternating current flowing charging the control condenser 18a is fed by lines 23 and 24 through a rectifier 25 and the rectified current flows through lines 26 and 27 to the secondary condenser 28. The peak voltage built up on the condenser 28 will be proportional to the average value of the alternating current charging condenser 18a no matter what the shape of the current wave. The potential built up on the condenser 28 is fed through lines 26 and 29, compensating voltage 30a, 30b or 30c, and lines 31 and 32 to the cathode 33 of the amplifier tube 34. The control grid 35 of the amplifier tube is provided with a suitable bias through the variable resistor 36 and lines 31, 38, contacts 39 and line 40. The screen grid 41 of the amplifier tube is provided with a suitable bias through line 42 and resistance 43. The circuit through plate 44 of the amplifier tube includes line 45, the D. C. winding 46 of a saturable reactor 47, line 48, condenser 49 and line 50. Tube 34 thus provides a modulator device for varying the heating effect of filament 12 responsive to variations in the peak voltage of condenser 28.

The relationship in the control circuit for amplifier tube 34 is related to the normal expected voltage on condenser 28 corresponding to the desired current flow charging the control condenser 18a. The compensating voltage shown at 30a, 30b or 30c is arranged to buck the potential of condenser 28 and the relationship is such that the potential of condenser 28 minus the compensating voltage equals the bias on the control grid 35.

Any suitable means may be provided for providing the necessary circuits for amplifier tube 34 including the plate voltage, grid bias, compensation voltage and screen grid voltage. The means shown comprises a transformer 51 having a primary 51a supplied from a suitable source L5, L6. The main secondary winding of this transformer 51b is connected through a rectifier 52 so as to provide rectified current through lines 53 and 54 to lines 50 and 48 respectively. The smoothing condenser 49 performs its usual function. A secondary winding 55 may be provided for heating the cathode of the rectifier tube 52. Another secondary winding 56 may heat the cathode for amplifier tube 34 and other windings 57 are provided for the rectifier 25. The proper connections from the windings 56 and 57 are omitted for clearness. Preferably, a voltage regulator tube 58 of the VR150 type provides stabilized voltage for the compensated voltage windings and for the screen grid. Preferably, also a voltage regulator tube 59 of the VR75 type provides stabilized voltage for the control grid bias.

Means is provided for varying the heating current for filament 12 responsive to changes in the plate circuit of tube 34. Many devices might be used, but I have chosen the saturable reactor 47. It is well known that the passing of a direct current through the winding 46 of this reactor has

a considerable controlling influence on the alternating current flowing through the windings 60 of this reactor. For a very low D. C. magnetization of the core of the reactor, the impedance is at a maximum. For full D. C. saturation of the core, the impedance is at a minimum. The A. C. windings of the reactor (of which a plurality may be provided as shown) are connected by selector switch 61 and lines 62 and 63 in series with the primary winding 64a of a transformer 64 whose secondary winding 64b is connected by lines 65 and 66 with the X-ray tube filament 12.

Referring back to the relay 22 previously mentioned, it will be noted that besides the pair of normally closed contacts 39 influenced by this relay, there is also a pair of normally open contacts 39a. It results from this construction that when the button 21 is depressed for an X-ray exposure, relay 22 is energized causing contacts 39 to open and causing contacts 39a to close. The opening of contacts 39 removes the normal bias from the control grid 35 of the amplifier tube 34. At the same time this grid is connected by line 40, contacts 39a and lines 67 and 27 with the negative side of condenser 28. If the desired current is flowing in the central secondary circuit and charging the condenser 18a then the normal expected potential will be developed in the condenser 28. This voltage minus the bucking voltage provided at the compensating voltage 30a will then equal the normal bias on the grid 35. Thus, there will be no change in the bias of grid 35, there will therefore be no change in the current flowing in the plate circuit and there will be no change in the filament heating current.

Under conditions similar to those of the preceding paragraph, if the contactor is closed for an exposure and the X-ray tube current is too high, then the condenser 28 will be charged above the normal expected potential and when the compensating voltage is deducted from this amount it leaves a greater negative bias upon the control grid 35. This decreases the plate voltage and therefore the direct current flowing in the winding 46 of the saturable reactor 47. This increases the impedance of the A. C. windings 60 and decreases the current in the A. C. circuit feeding the filament transformer primary. This cuts down the current in the filament transformer secondary 64b so that the heating effect of the filament 12 is cut down until the current flowing in the X-ray tube is that desired.

Under similar conditions if the contactor is closed for an X-ray exposure and the X-ray tube current is too low, then the condenser 28 is charged below the normal expected potential and when the compensating voltage is deducted from this potential it leaves a bias on grid 35 which is more positive than normal. This will increase the plate current and therefore the direct current in the winding 46 of the saturable reactor 47. This decreases the impedance of the A. C. windings 60 and increases the current in the A. C. circuit feeding the filament transformer. Therefore the filament current will increase until the tube load comes up to that normal or desirable amount.

In order to shorten the time necessary to fully charge condenser 28 to the potential necessary to compare with the normal desired potential, I may provide a second pair of normally closed contacts 68 under the influence of relay 22. These contacts are normally closed and by means of lines 69 and 70 complete a circuit which connects the condenser 28 to the control grid bias and the

compensating voltage so that condenser 28 is charged to the expected normal potential prior to the moment an exposure is initiated. At such time relay 22 is energized coincidentally with relay 20 and contacts 68 are opened at the same time that contacts 39a are closed for the purpose previously mentioned.

In case the voltage on the condenser 28 needs to be slightly lowered, a bleeder resistor 74 is provided which is connected across condenser 28 by lines 72 and 73 and contacts 68a when relay 22 is energized. The resistor 74 is so dimensioned that the discharge is not greater than ten percent of the condenser charge for one-half cycle.

By properly selecting the condenser 18a and the peak voltage to which the condenser 28 is charged, suitable conditions may be selected corresponding to various desired current flows in the central secondary grounded circuit of the transformer 16. In one case I utilize a condenser 18a of one-quarter microfarad, and a current of five milliamperes flowing in the central secondary grounded circuit will charge the condenser 28 up to a peak voltage of eighty-three volts. Under these circumstances I use a compensating voltage 30a of seventy-one volts and a bias on the grid 35 of twelve volts. If the condenser 18b is 1 m. f. d., I may provide a switch 74 having a contactor 74a adapted to connect condensers 18a and 18b simultaneously giving a capacity of one and one-quarter m. f. d. If now the condenser 28 is charged to a peak of eighty-three volts this will correspond to a current flow of twenty-five m. a. in the central secondary grounded circuit. If, under the same conditions, the condenser 28 is charged to a peak voltage of one hundred and sixty-six volts this will correspond to a tube current of fifty m. a. This may be arranged by changing the compensating voltage 30b to one hundred and fifty-four volts utilizing a contact arm 76 which is a portion of a selector 79 which may be connected with the switch 74 by means indicated diagrammatically at 78. Thus, a monitor control might be arranged simply to be set at twenty-five m. a. by turning the switch 74 to connect the buttons A and B together while at the same time selecting seventy-one volts on the variable compensating voltage 30b. In similar manner, fifty m. a. might be selected by setting the compensating voltage 30b for one hundred and fifty-four volts. If the condenser 18c were of four m. f. d. capacity then the switch contactor 74a might be turned to connect the buttons B and C simultaneously giving a total capacity in the condensers 18b and 18c of five m. f. d. This would correspond to a tube current of one hundred m. a. when the condenser 28 is charged to a peak voltage of eighty-three volts. By means of suitable arrangements the contact arm 76 may be arranged to select a compensating voltage at 30c of either seventy-one volts or one hundred and fifty-four volts as previously explained in connection with 30b. In case one hundred and fifty-four volts is selected then condenser 28 may be charged to a peak voltage of one hundred and sixty-six volts which will correspond to a tube current of two hundred m. a. These figures are representative only and illustrate how by a proper selection of the condenser 18a and 18b or 18c and the proper compensating voltage, various desired tube currents may be automatically selected.

The purpose of arm 77 and contacts 77a is to insure the connection of the resistor 30a, 30b or

30c, selected by arm 76, in circuit from line 48 through resistors 30 and 81 and line 82 to line 31. The voltage regulator tube 58 insures constant voltage across resistors 30a, 30b or 30c.

5 What I claim is:

1. The combination of an X-ray tube provided with a heated filament, means for heating said filament, an energizing circuit for said tube including a high tension transformer having a secondary with a central grounded circuit, the output of said secondary being electrically connected with the anode and cathode of said tube, a control condenser in said central grounded circuit, means for rectifying current charging said condenser, a secondary condenser electrically connected to receive said rectified current and to be charged thereby, an amplifier tube having a plate and a cathode and a control grid, a normally open comparison circuit including said secondary condenser and said amplifier cathode and said grid, normal potential for said secondary condenser corresponding to the desired current flow through said control condenser in said central grounded circuit, means in said comparison circuit for applying a compensating voltage bucking said normal potential of said secondary condenser, means for applying a bias to said control grid equal to said normal potential minus said compensating voltage, a plate circuit including said plate of said 10 amplifier tube, means in said plate circuit for controlling said filament heating means responsive to current flow in said plate circuit, and means for disconnecting said bias applying means and for closing said comparison circuit coincident with energization of said X-ray tube, whereby variations in said normal potential due to undesired flow in said central grounded circuit will vary the bias on said control grid and vary the current flow in said plate circuit, said means in 15 said plate circuit for controlling said filament heating means being electrically responsive to increased or decreased current flow in said plate circuit to increase or decrease respectively the effect of said heating means.

2. The combination of an X-ray tube provided with a heated filament, means for heating said filament, an energizing circuit for said tube including a high tension transformer having a secondary with a central grounded circuit, the output of said secondary being electrically connected with the anode and cathode of said tube, a condenser in said central grounded circuit, means for rectifying current charging said condenser, a secondary condenser electrically connected to receive said rectified current and to be charged thereby, normal potential for said secondary condenser corresponding to the desired current flow through said first named condenser, means normally charging said secondary condenser substantially to said normal potential, and circuit means effective only when said X-ray tube is energized and electrically associated with said secondary condenser and with said filament heating means for increasing and decreasing the effect of the latter responsive to decrease and increase respectively in potential across said first named condenser.

3. The combination of claim 1 including a plurality of said control condensers, a plurality of said compensating voltage applying means, and common means for selecting a desired control condenser and a desired compensating voltage applying means.

4. The combination of an X-ray tube provided with a heated filament, an energizing circuit for

said tube, heating means for said filament, a control device for said heating means, a condenser connected to said energizing circuit so as to build up a peak voltage in said condenser in response to discharge current through said tube, and a modulator device having a control element in circuit with said condenser and varying with the peak voltage of the latter, said modulator device having a controlled element in circuit with said control device for decreasing and increasing the heating of said filament responsive to increase and decrease respectively of the peak voltage of said condenser.

5. The combination of an X-ray tube provided with a heated filament, means for heating said filament, a control device for said heating means, an energizing circuit for said tube, means in said tube circuit for electrically integrating the current flowing therein during successive half waves, and a modulator device having a control element in circuit with said integrating means and varying with the peak voltage of the latter, said modulator device having a controlled element in circuit with said control device for decreasing and increasing the heating of said filament responsive to increase and decrease respectively of the peak voltage of said integrating means.

6. The combination of an X-ray tube provided with a heated filament, an energizing circuit for said tube, heating means for said filament, a control device for said heating means, a condenser having electrical connections with said tube for subjecting said condenser to a peak voltage charge which is an integration of successive current waves in said tube circuit, a space discharge tube having a filament and a plate and a control grid, an electrical connection between said condenser and said control grid, and a plate circuit including said plate and said control device for said filament heating means for increasing and decreasing said filament heating means responsive to increase and decrease in current in said plate circuit.

7. The combination of an X-ray tube provided with a heated filament, an energizing circuit for said tube, heating means for said filament, a control device for said heating means, a condenser having electrical connections with said tube for subjecting said condenser to a peak voltage charge which is an integration of successive current waves in said tube circuit, electrical means for applying a predetermined desirable potential to said condenser independent of said peak voltage, a space discharge device having a control grid and a filament and a plate, switch means normally connecting said electrical means with said grid for applying said predetermined potential thereto, control means operable concurrently with energization of said X-ray tube for disconnecting said switch means normal connection and for applying said peak voltage to said control grid, and an electrical circuit including said plate and said filament heating means control device for increasing and decreasing said filament heating means responsive to increase and decrease respectively of current in said electrical circuit including said plate, whereby to hold the current flowing in said X-ray tube substantially constant.
